UNITED STATES PATENT OFFICE.

EDWARD A. LANGENBACH, OF CANTON, OHIO.

DESIGN FOR A CEILING-PLATE.

SPECIFICATION forming part of Design No. 26,240, dated November 3, 1896.

Application filed September 23, 1896. Serial No. 606,786. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Ceiling-Plates, of which the following is a full, clear, and exact description, reference being had to the accompanying drawings, making part of this specification.

The invention relates to a new design for metallic ceiling-plates; and it consists of a ceiling-plate of the form and ornamentation shown in the accompanying drawings, in which—

Figure 1 is a plan view of the ceiling-plate, and Fig. 2 is a sectional view.

The leading feature of the design is a plate A, square in outline, having at its center a raised semispherical portion 1, from which radiate ribs 2, that are inclosed within a scalloped raised border 3, encircled by an annular rib 4, which is inclosed within an ab-

ruptly-raised portion 5, having annular ribs 6, knobs or buttons 7, and scallops 8. Surrounding the abruptly-raised portion of the plate is the sunken portion, which is ornamented by the scrolls 10, the leaf-like figures 11, the triangular figures 12 at the corners, and the raised alternating ribs and buttons 13 and 14, respectively.

A ceiling-plate constructed and ornamented as above described and as shown in the accompanying drawings is both neat and attractive and greatly adds to the general appearance of the room or hall in which it is used.

What I claim is—

The design for a metallic ceiling-plate as herein shown and described.

In testimony whereof I have hereunto set my hand this 30th day of July, A. D. 1896.

EDWARD A. LANGENBACH.
